[57] **CLAIM**

The ornamental design for a cover for bathtub spout, as shown and described.

DESCRIPTION

FIG. 1 is a front elevational view of a cover for bathtub spout showing my new design;

FIG. 2 is a rear elevational view thereof;

FIG. 3 is a right side elevational view thereof, the left side being a mirror image of the right side shown;

FIG. 4 is a top plan view thereof; and,

FIG. 5 is a bottom view thereof.

FIG. 1

FIG. 2

FIG. 3

FIG. 4

FIG. 5
